GASEOUS ELECTRIC DISCHARGE DEVICE

Otto Fritze, Berlin, Germany, assignor to General Electric Company, a corporation of New York

Application June 2, 1937, Serial No. 146,047

In Germany June 9, 1936

2 Claims (Cl. 126-134)

The present invention relates to gaseous electric discharge devices generally and more particularly the invention relates to gaseous electric discharge lamp devices comprising thermionic electrodes which are heated to a high electron emitting, arc discharge supporting temperature prior to the initiation of the gaseous electric discharge therebetween.

In co-pending application, Serial Number 642,882, filed November 16, 1932, inventor Andrew H. Young, a gaseous electric discharge device of the above type is disclosed which comprises electrodes which are initially heated to an elevated temperature by the passage of current and a conductor comprising a thermostatic switch which conductor, when the switch is in its closed circuit position, connects the heater elements of the electrodes in series across the terminals of the current source for said device and short-circuits the discharge path between the electrodes. The thermostatic switch is mounted external to the container of the device and in heat receiving relation to some part thereof, such as the container wall adjacent one of the electrodes, so that when the electrode temperature rises to a value at which the electrode is capable of supporting an arc discharge without appreciable disintegration the thermostatic switch moves to its open circuit position and the discharge starts between the electrodes.

30 electrodes.

The object of the present invention is to provide a longlived gaseous electric discharge device of the above type comprising a thermostat protected from the ambient without the need of protecting means external to the lamp container and which thermostat is positive in operation. Still further objects and advantages attaching to the device and to its use and operation will be apparent to those skilled in the art from the following 35 particular description.

40 particular description.
The invention attains its objects by enclosing
the thermostatic switch in an hermetically sealed
vessel and by mounting said vessel closely adja-
cent one of the electrodes in the container of the
45 gaseous electric discharge device. The sealed
vessel is either highly evacuated or is filled with
a gas, such as hydrogen, under substantial pres-
sure to suppress any arc between the contacts of
the switch.

50 The thermostatic switch is intensely heated by the heat emanating from the electrode and is, therefore, positive in operation. When desired, a heat retaining element, such as a hollow metal cylinder open in the direction of the discharge 55 path, surrounds the electrode and the thermo-

static switch is mounted in the space between said electrode and said heat retaining element.

The thermostatic switch is provided with two current leads one of which is connected to the heater element of the electrode adjacent the switch and the other of which is connected into an auxiliary starting circuit. The external part of the current lead which is connected to the auxiliary circuit is coiled helically and engages with a similarly coiled lead of the auxiliary circuit. The mounting of the thermostatic switch in the container of the device is simplified by this structure since welding operations in close proximity to vitreous parts of the lamp container or of the switch vessel are avoided.

In the drawing accompanying and forming part of this specification an embodiment of the invention is shown, in which—

Fig. 1 is a side elevational, partly sectional view of one embodiment of the invention and

Fig. 2 is a similar view showing in detail an end assembly of the device illustrated in Fig. 1.

Like numbers denote like parts in both the figures.

Referring to the drawing the gaseous electric discharge lamp device comprises an elongated, tubular container 1 having a gaseous atmosphere therein, such as rare gas at a pressure of about 1 to 10 mm., metal vapor, or a mixture of starting gas and metal vapor, which is luminosity producing during the operation of the device. Thermionic activated electrodes 2 and 2' are mounted in the ends of said container 1. Each of said electrodes 2 and 2' consists of a rod of electron emitting material, such as barium oxide, and a heater filament, such as a tungsten filament wrapped around said rod. Said electrodes 2 and 2' are surrounded by heat conserving shields 3 and 3', respectively, and said shields 3 and 3' having openings 4 and 4', respectively, therein in the direction of the discharge path between electrodes 2 and 2'. The gaseous electric discharge device is connected across the terminals 5 of a 220 v. alternating current source. A choke coil 6 is connected in series with said gaseous electric discharge device and a switch 7 is provided for connecting and disconnecting said device across the terminals 5. Said electrode 2 is supported by a current lead 8 and the support 8'' fused into the press 17 of the stem of said container 1 and the electrode 2 is similarly supported at the opposite end of the said container 1. The shields 3 and 3' are supported by a support wire attached thereto, as by welding, which wire is fused into the press of said stems. The stem at 55

one end of the container 1 is provided with the exhaust tube 16.

The bimetallic switch 10 (shown in detail in Fig. 2) consists of an hermetically sealed vitreous container 11 having a contact 12 and a bimetallic strip 14 mounted therein. When said strip 14 is sufficiently heated it moves from its contact making position to its contact breaking position (indicated at 13 in Fig. 2). The contact 12 of the switch is connected by lead 19 to the support wire 8" of the electrode 2 and the bimetallic strip 14 of the switch is connected by lead 15 to the current lead 9. The external end of the current lead attached to the bimetallic strip 14 is coiled helically (as shown at 20) and is fastened to the end of the current lead 15, which is similarly coiled, by screwing these elements together during the assembly of the device. As shown in Fig. 1 the current lead 9 is connected to the electrode 2' at the opposite end of the container 1. When potential is first applied to the lamp device by closing switch 7 the bimetallic switch 10 is in a contact making position and current flows through the heater coils of the electrodes 2 and 2', the bimetallic switch 10 and the conductor 9, short-circuiting the discharge path between said electrodes 2 and 2'. The flow of current therethrough heats the electrodes 2 and 2' to an electron emitting, arc discharge supporting temperature and the heat emitted by the electrode 2 heats the bimetallic switch 10. In response to this heating the strip 14 bends and moves to a contact breaking position. When contact is broken in the switch 10 potential is impressed across the terminals of the discharge device and a discharge starts between the electrodes 2 and 2'. During the operation of the device the electrodes 2 and 2' are maintained at an electron emitting discharge supporting temperature by the arc discharge incident thereat and the bimetallic strip 14 is maintained in its contact breaking position by the heat emitted by said electrode 2.

While I have shown and described and have 45 pointed out in the annexed claims certain novel

features of the invention, it will be understood that various omissions, substitutions and changes in the forms and details of the device illustrated and in its use and operation may be made by those skilled in the art without departing from the broad spirit and scope of the invention, for example, when high frequency starting is desired the bimetallic switch 10 is used to control the operation of the high frequency apparatus, when desired, or the bimetallic switch 10 is used 10 to control the operation of an auxiliary starting discharge in the device when that method of starting is used, and, when desired, the current lead 9 is covered with an insulating material, such as glass, and is mounted inside of the container 1. 15

What I claim as new and desire to secure by Letters Patent of the United States, is:

1. A gaseous electric discharge lamp device comprising a sealed container, a gaseous atmosphere therein, electrodes sealed therein which are electron emitting when heated, a thermostatic switch mounted in said container and in heat receiving relation to one of said electrodes, a heat retaining means surrounding one of said electrodes and said switch, said switch consisting of a sealed vessel having a bimetallic strip and a contact therein, and an auxiliary starting means for said device, said starting means being controlled by said switch. 30

2. A gaseous electric discharge lamp device comprising a sealed container, a gaseous atmosphere therein, electrodes sealed therein which are electron emitting when heated, a thermostatic switch mounted in said container and in heat receiving relation to one of said electrodes, said switch consisting of a sealed vessel having a bimetallic strip and a contact therein, and an auxiliary starting means for said device, said starting means being controlled by said switch, 35 said switch having a helically coiled current lead engaging with a similarly coiled lead of said starting means. 40
